NICHOLAS S. VEDDER, OF TROY, AND TOBIAS S. HEISTER, OF LANSINGBURG,
ASSIGNORS TO JOHN A. GOEWY, OF ALBANY, NEW YORK.

Design No. 4,900, dated May 9, 1871.

DESIGN FOR A COOKING-STOVE OR RANGE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer and State of New York, have jointly invented and produced a new and original Design for Stoves or Ranges, of which the following is a specification, reference being had to the accompanying photographs of a range or stove having our said design.

One part of our design consists of an ornamental initial letter, "G," shaped and arranged on a panel or surface of a door, plate, or leg of a stove or range, so as to appear substantially as shown at *a* in the aforesaid photographs.

Another part of our design consists of the initial letters "J. A. G.," shaped and arranged upon a panel or surface of a door or plate of a range or stove so as to present an appearance substantially the same as is represented in the accompanying photographs.

Another part of our invention is the ornamental corner-piece and border *b c*, shaped and arranged upon a plate, door, or panel of a range or stove, as shown by the accompanying photographic representations.

Another part of our invention is the ornamental corner-piece and border *d e*, shaped and arranged on a plate or panel of a stove or range, as shown by the aforesaid photographs.

Another part of our design is the ornamental molding *f*, when shaped and arranged in connection with the moldings *g* and *h*, on a door or plate of a stove or range, as shown in the photographs.

Another part of our invention is the row of ornamental figures *i*, shaped and arranged along and upon the upper portion of a side, front, or end plate of a range or stove, as shown in the aforesaid photographic representations.

What we claim as our invention, and desire to secure by Letters Patent, is—

1. The initial letter "G," shaped and arranged upon a plate, panel, or leg of a stove or range, so as to appear as herein set forth.

2. The initial letters "J. A. G.," shaped and arranged upon a plate or panel of a range or stove, as herein described.

3. The ornamental corner-piece and border *b c*, shaped and arranged on a plate or panel of a stove or range, as set forth.

4. The ornamental corner-piece and border *d e*, shaped and arranged on a panel or plate of a stove or range, substantially as described and shown.

5. The ornamental molding *f*, arranged between and in relation to the moldings *g* and *h*, on a plate or door of a range or stove, as described.

6. The row of ornamental figures *i*, arranged along and upon the upper portion of a plate or plates of a stove or range, as set forth.
